MATERIAL FOR SCOURING UTENSILS

Application filed December 4, 1930. Serial No. 500,022.

This invention relates to an improved arrangement of material for scouring utensils. A particular utensil in which the new material can be used to advantage is shown in my copending application Serial Number 474, 551, filed August 11, 1930.

In utensils of this general character, the common practice has been to use a textile carrier cord on which a flattened metallic filament is twisted. The twisted or gimped filament provides scouring edges. My invention consists in changing the character of the carrier around which the metallic filament is twisted. In one form of the invention I use 15 the same kind of filament for the carrier as is used for the element twisted about the carrier. To increase the effect of this change I may use two or more such filaments instead of one for the carrier means and twist one or 20 more filaments about the carrier means. The latter combination gives a loose bundled arrangement of the carrier filaments which are not twisted to carry the filament or filaments which are twisted. By the new combination 25 more scouring edges are provided than in the old, and other advantages are obtained as will be pointed out with respect to the utility of a scouring utensil with the new arrangement of material.

30 A complete understanding of the invention is given by the accompanying drawings and description of the advantages in the new combination. In the drawings—

Fig. 1 is a plan and

35 Fig. 2 is an end view of the carrier means in multiple form;

Fig. 3 is a view of the carrier filament with another filament of like character twisted about it into gimped form; and

40 Fig. 4 is a view of a scouring utensil such as is made up from the material shown in Fig. 3.

The filament 1 is or may be made of copper, or steel which is coated with copper or 45 given an anti-rust treatment or is made of an anti-rust alloy. It is such a filament as has been used ordinarily for the twisted part of the made-up strand in a scouring utensil of my type, but may differ by providing a stronger filament. As a modification I may

use a textile carrier cord and assemble with this cord one or more flattened filaments in untwisted form about which assembled carrier I twist one or more flattened metallic filaments. In the latter case the textile cord 55 will provide an emergency carrier if the carrier filaments break, but the latter will function to scour in any event. To practice my new invention I use a single filament 1 or a plurality of them, as shown in Fig. 2, as the 60 carrier, and twist about it coils 2 of another filament of about the same kind. But the filaments 1 and 2 are all flattened so as to present scouring edges. The carrier 1, while it is not purposely twisted, may nevertheless 65 turn somewhat. The gimped or twisted strand 2 is loosely mounted on the carrier 1 with many turns to the inch about carrier 1 to increase the scouring edges.

When the combination of Fig. 3 is used in 70 a scouring utensil the coils of strand 2 being loose are spread apart and pushed together, due to the rubbing action. When they spread apart the edges of metallic strand or strands 1 occupy the space between and are 75 in a position to function also as a scouring element and as a scraping element at the points where the coils have separated widely. In a scouring utensil such as shown in Fig. 4 the total effective scouring surface is greatly 80 increased by the new arrangement or combination of material making up the utensil. And this would be true also if other specific forms of scouring utensils were made up of 85 the new arrangement of material.

The utensil shown in Fig. 4 is made up except for the material of the carrier cord like the one more fully described in the above referred to copending case. That is, the combination of carrier filament 1 and coiled filament 2, as shown in Fig. 3, is looped into skein form. Each skein loop passes twice through two circular binding elements 4 and 5. By arranging the binding elements 4 and 5 at directly opposite points in the skein loops, the material of the skein between the binding elements is left in loose but regularly arranged form. The result of such arrangement with the material shown is like a puff ball. The effect is improved by the charac-

ter of the carrier filament. There is just enough spring in the metallic carrier to effect a better holding of or return to the puff ball shape after use. In other words, the carrier filament makes the utensil just a little stiffer in form and yet yieldable enough for its function. The filaments which carry the gimped strands can and do act as scouring and scraping elements where the gimped strand is moved along or spread out. Furthermore, the bright appearance of the ball when made entirely of flattened filament is enhanced. The binding elements 4 and 5 are preferably of stiff wire so the whole utensil is of metal but in form to be easily cleaned.

15 What I claim is:

1. The combination for scouring purposes of two flattened metallic filaments, one arranged as a straight strand for carrying the other and the latter loosely coiled or gimped about the first so that the combined all-metal strand has scraping edges throughout its length, some on the carrier strand and some on the gimped strand.
- 25 2. An improved structure for scouring purposes of a plurality of loosely arranged parallel flattened metallic filaments in untwisted form and providing a carrier means, a metallic filament loosely twisted or gimped about the carrier means to make with the carrier a composite scouring strand in which scouring edges are provided by both the carrier and the gimped elements.

30 In testimony whereof I have affixed my
35 signature.
